LIQUID HEATER

Filed June 4, 1928

Patented June 25, 1929.

1,718,865

UNITED STATES PATENT OFFICE.

BARNETT W. MACY, OF JACKSONVILLE, FLORIDA.

LIQUID HEATER.

Application filed June 4, 1928. Serial No. 282,530.

This invention relates to improvements in liquid heaters, and it consists of the constructions, combinations and arrangements herein described and claimed.

5 An object of the invention is to provide a water or other liquid heater, having a heating unit which is both of novel construction and has an associated thermostat by which the electrical heating current is controlled without either supervision or aid.

Other objects and advantages appear in the following specification, reference being had to the accompanying drawing, in which

15 Figure 1 is a vertical section of a sheathed water or liquid tank and the heating unit in place therein,

Figure 2 is a detail section of the upper part of the heating unit,

20 Figure 3 is a detail section of the lower part of the heating unit, particularly illustrating the thermostat;

Figure 4 is a cross section taken on the line 4—4 of Figure 3.

In considering this invention attention 25 may be paid to a co-pending application for patent on heating devices filed on September 21, 1927 by B. W. Macy, Serial 221,112. The structure is that application includes an oil-filled cylinder which contains a sleeve of insulating material upon which coils of electrical resistance wire are wound in opposite directions, a thermostat being associated with the coils and contained by the cylinder.

35 The same principle obtains in the present instance, but refinements of both structure and arrangement have been made, thus composing an invention of novelty in view of the disclosure in the application mentioned.

40 One of the outstanding improvements relates to that structure which permits the abstraction of the entire heating unit from its working position within a tank, without either cutting off the water from the city mains, or draining the tank. This facility owes its origin to the fact that the heating unit is sheathed by a heater tubing that depends permanently within the tank, it being from this tube that the heating unit may be abstracted with impunity so far as the city 45 water pressure is concerned.

50 Reference is made to the drawing. A tank 1 of any known type, and for the purpose of containing any desired liquid to be heated, such as water, has a thick sheathing of insulation 2 to keep the contents hot as long as possible. This sheath-

ing is held in place by an outside jacket 3. A pipe or tube 4, welded at 5 in the top of the tank 1 extends to a point close to the bottom of the tank, but is closed at that end. The upper end of the heater tube, for such is its designation in this description, extends to a point outside of the jacket 3 where a connection ring 6 is cemented or otherwise secured in place. 65

This ring provides for the attachment of a heating unit by means of screws 7 that pass through the flange of a base plate 8 forming part of the heating unit. By removing the screws 7 the entire heating unit may be 70 lifted out of the tube 4 without either draining the tank 1 or cutting off the water from the city mains. The inlet of the latter is indicated at 9, and the outlet 10.

Two terminal rods 11 and 12 extend from 75 the base plate 8 to a point adjoining a spacer bar 13 where they carry suitable connectors 14 to which the upper ends of resistance wires or heating elements 15 are attached. The wires are coiled, and the lower ends are 80 threaded through holes 16 in a bottom spacer bar 17 before they are respectively connected with the yieldable element 18 and to the contact bar 19 of a thermostat. The latter connection is made through a length 20 of 85 beaded wire.

Suitable bushings 21 and washers 22 insulate the rods 11 and 12 from the base 8. The exposed ends of these rods have any usual arrangement of nuts 23 by which the 90 wires of an electrical circuit may be secured. A cover 24 protects the terminal connections. This cover slips over the edges of the ring 6 and base 8 as shown in Figure 1.

A stud 25, co-extensive with the heating 95 unit, supports the bottom spacer bar 17. The ends of the stud are threaded, respectively to permit screwing into the base 8, and to receive a nut 26 which locks the assembly. An upper porcelain sleeve 27, 100 through which the stud passes, fixes the position of the top spacer bar 13 in reference to the base 8. A lower porcelain sleeve 28, through which the stud also passes, fixes the relationship of the upper and lower spacer 105 bars. Each of the latter is of insulating material.

The thermostat is suitably affixed to the lower sleeve 28, and comprises the following construction: a base 29, preferably of 110 sheet brass, including a guide strap 30 by which a jointed breaker arm 31 is held in

position and guided in its movements. The joints of the arm are pivoted together at 32 and to the base at 33. Stops 34 limit the movements of the arm.

- 5 One end of the upper arm joint carries a contact which is engageable with another contact on the contact bar 19. That bar is secured to the base 29 as at 35, but is insulated therefrom at 36 as plainly shown in
10 Figure 4. One end of the other arm joint is forked at 37 to receive the free end of the yieldable element 18. That element is electrically connected with the base.

A ball check-valve 38 provides for the release of any gas under pressure in the heater tube 4. This valve has connection with the tube through a pipe 39. The tube 4 will be filled with oil of a suitable kind, the effect of the elements 15 being to heat the oil and
20 tube 4, hence the liquid in which the latter is immersed will be heated.

The operation is readily understood. Upon completing an electrical circuit through the elements 15 the latter will act to
25 heat the oil within the tube 4, which latter will heat the water or other liquid within the tank 1. When the heat reaches a degree to cause flexing of the thermostatic element 18 into the dotted line position the resulting
30 rocking of the joints of the arm 31 will separate the electrical contacts at the bar 19 and open the circuit until the internal temperature drops sufficiently to permit flexing of the element 18 to the full line position. An
35 automatic control is thus effected.

Not of the least importance is the specific manner in which the heating unit is combined with the tank 1. The tube 4 constitutes a fixed part of the tank, being welded
40 in place as at 5. It is virtually a receptacle for the heating unit. All of the elements of the latter are carried by the base plate 8, and when the base plate is loosened from the connecting ring 6 the heating unit may
45 be abstracted from the tube 4 without so much as cutting off the city water or draining the tank 1.

While the construction and arrangement of the improved liquid heater is that of a
50 generally preferred form, obviously modifications and changes may be made without

departing from the spirit of the invention or the scope of the claims.

I claim:

1. A heater comprising a tank, a closed-ended tube extending into and secured to the tank, and an electrical heating unit insertable into the tube comprising the following: a base plate securable to the tube, a heating element, terminal connections for said element including a thermostat and a pair of rods depending from the base plate, a pair of insulating sleeves to one of which the thermostat is attached, spacer bars for the heating element being spaced from each other and from the base plate by said sleeves, and a stud co-extensive with the heating unit, holding the parts of the latter assembled.

2. A heater unit comprising a base plate, resistance wires, a pair of terminal rods depending from the base plate and being respectively connected with one end of each wire, a yieldable element to which the remaining end of one wire is connected, a contact bar with which the other end of the remaining wire is connected, a jointed arm operable by the yieldable element, a base to which said element and arms are attached, insulating sleeves by one of which said base is carried, spacer bars for the resistance wires, being spaced from each other and from the base plate by said sleeves, and a stud running through the bars and sleeves holding the parts of the unit assembled.

3. A heater tube containing a quantity of oil and being immersible in a fluid to be heated, an electrical heating unit supported in the tube and immersed in the oil, and a thermostat included in an electrical circuit which embraces the heating unit, also being immersed in and subject to the heating and cooling of the oil at set temperatures for operations to open and close the circuit.

4. A heater tube containing a column of oil, an electrical heating unit immersed in the oil, and a thermostat forming part of the terminal connections of the heating unit and being located adjacent to one extremity of the column of oil.

BARNETT W. MACY.
